UNITED STATES PATENT OFFICE.

GEORGE B. PICKOP, OF NEW HAVEN, CONNECTICUT, ASSIGNOR TO MALLEABLE IRON FITTINGS COMPANY, OF BRANFORD, CONNECTICUT.

VIBRATOR OR AGITATOR.

Application filed December 26, 1922 Serial No. 609,037.

This invention relates to vibrators or agitators, and more particularly to a device adapted to shake or agitate a screen or riddle which may be used for many purposes such as screening sand, mixing paints or the like, or in connection with screening chutes or agitating dust collector screens. While I have chosen to illustrate my invention as applied to a riddle or a screen device, it will 10 of course be understood that it is capable of broad application and is not limited to the particular details or to use in the particular combination shown.

In the past, agitating or vibrating devices of this general character have sometimes been provided with an overbalanced or eccentrically weighted rotating wheel, this wheel usually being driven by an electric motor mounted near the top of the frame, 20 and to connect the rotor of the motor with the rotating wheel it is necessary to arrange a shaft between these two members and connect it flexibly with at least one thereof. As a general thing there is a great deal of 25 dust and dirt around apparatus of this kind, and the life of an electric motor under such conditions is very short. Moreover, the gyroscopic movement of the whole vibrator frame tends to wear out the bearings of the motor 30 and the maintenance of such a device is found to be more or less expensive.

One object of my invention is to overcome the disadvantages referred to above and provide an agitator or vibrator which will be 35 very simple in construction and which will have no parts liable to be seriously affected by the dirt or dust incident to the operation of such a device.

Another object of my invention is to simplify devices of this character by providing 40 for the use of the vibrator or overbalanced wheel as the main power element.

Another object of my invention is to simplify devices of this character by applying 45 the source of power directly to the vibrator or overbalanced rotor so that a separate motor or power device will be unnecessary.

Another object of my invention is to produce an agitator which will be more effective in operation than those heretofore made and will at the same time be economical in 50 operation and will have very few parts which will be subject to any wear in operation.

To these and other ends the invention con-

sists in the novel features and combinations 55 of parts to be hereinafter described and claimed.

In the accompanying drawings,

Fig. 1 is a side elevational view of a vibrat⁶⁰or embodying my improvements;

Fig. 2 is a top plan view of the same;

Fig. 3 is a bottom plan view of the vibrat⁶⁵or;

Fig. 4 is a sectional view on line 4—4 of Fig. 3;

Fig. 5 is a top plan view on line 5—5 of Fig. 4, with the riddle or screen removed;

Fig. 6 is a sectional view on line 6—6 of Fig. 5; and

Fig. 7 is a side elevational view of a modified form of my invention.

In the preferred form of my invention which I have chosen to illustrate and describe, I have shown a vibrator or agitator comprising a frame, consisting generally of 75 a pair of vertically disposed rods 10 and 11 which are connected at their lower ends to a cylindrical drum or housing 12 open at the top and bottom. The upper ends of the rods may be joined by a link 13 which has 80 an opening or perforation 14 so that it may be suspended from a hook or like supporting device 15.

Within the cylindrical drum 12 is secured 85 a spider consisting of the three arms 16, 17 and 18, which carry, at the center of the drum, a bearing socket 19. This bearing socket may, of course, be of any preferred form, and likewise may be supported within the frame by other means than those described if desired. As shown in the drawing, 90 a grease cup 20 is provided upon the bearing socket 19 to insure the presence of sufficient lubrication at all times.

Within the bearing socket 19 is supported 95 upon ball bearings 21 of the usual or any approved form, a short, vertically disposed shaft 22. This shaft is provided with shoulder portions 23 and 24 to take care of the downward thrust incident to the operation of the device. A cap 24^a may be provided upon this bearing socket to prevent the entry of dust thereinto and suitable packing may be placed between the edge of the opening in this cap and the shaft 22.

Keyed at 25 to the upper end of the shaft 22 is a rotor or vibrator wheel 26. The plane of this wheel is at right angles to the

shaft 22 so that it lies in a generally horizontal position and the diameter of the wheel being substantially that of the inside of the cylindrical drum 12 so that the periphery of the wheel closely approaches the periphery of the drum. At one side the wheel is over-weighted, as at 27. In the form shown this is arranged by casting the wheel with an excess of metal at this point. It will be apparent that when the wheel, constructed in this way, is rotated, a gyroscopic motion will be imparted to the entire frame, which will produce an effective shaking or vibrating action upon the entire frame.

In the form of my invention illustrated, I have shown a riddle or screen 28 mounted in the upper part of the frame above the rotor. It will be apparent that in some aspects of the invention it is, of course, of no importance, as to the relative positions of the rotor and screen; that is to say, either one may be placed above the other. As shown, the screen is arranged to overhang the edge of the cylindrical drum 12 and is secured in position by a ring or annulus 29 and a number of clamps 30 of any approved form. As has already been stated, I choose to make my vibrator or agitating member the main power element by applying my source of power or source of potential energy directly thereto. In the form of my invention shown, this is accomplished by providing the periphery of the rotor 26 with a series of notches 31 forming blades 31^a which notches may be shaped in the proper manner to cause the wheel to be freely driven when a fluid under pressure is directed upon the periphery of the wheel through the nozzle 32 and hose 33. In foundry practice it will usually be preferable to drive the rotor by means of compressed air, although it will be obvious that other sources of power may be used, if desired, without departing from the principles of my invention. An apron 34, as shown in Fig. 5, is mounted above the rotor adjacent the nozzle 32, to insure that the fluid which is emitted under pressure from the nozzle will be directed downwardly and will not be permitted to pass upwardly to interfere with the material in the screen.

As shown in Fig. 6, the spokes or arms 35 of the rotor are inclined to the vertical so that there will be tendency for them to create a downward draft to carry the screened particles in that direction. Also, when the spokes are fashioned in this way, it will be apparent that any particles which impinge against the blades will be deflected downwardly and not up against the screen.

Also the spokes of the wheel striking the screened material will throw it against the arms 16, 17 and 18 of the spider, and thus will break up any solid particles which may have gotten through the screen.

In Fig. 7 of the drawings I have shown a

device similar in many respects to that illustrated and described in connection with Figs. 1 to 6, but which is in addition provided with a second screen 37 below the vibrating rotor, so that the material will be passed through the lower riddle as well as through the upper. The screen 37 is placed against the lower edge of the cylindrical drum 12, a ring 29 is engaged with the turned-over loop at the upper edge of the screen, and this ring is then clamped to the drum by means of the clamps 30.

It is obvious that when the hose 33 is connected with a source of compressed air or a similar source of energy, the vibrating rotor 26 will be caused to rotate at a relatively high speed. This rotor, being overbalanced, will at once impart a gyroscopic motion to the entire frame, which will effectively vibrate or shake the frame and riddle until the material in the riddle has been thoroughly screened. Moreover, it will also be apparent that notwithstanding the efficiency of the apparatus, it is composed of comparatively few parts, practically none of which is subject to excessive wear, and that there is no part of the mechanism which is likely to be seriously affected by the dust or dirt incident to the operation of the device.

While I have shown and described a preferred embodiment of my invention, it will be understood that it is not to be limited to the details shown, but is capable of many modifications and variations within the spirit of the invention and within the scope of the appended claims.

What I claim is:

1. In an agitator, a frame, including a circular housing, an agitating rotor rotatably mounted within the housing having its periphery formed to present blades and means to direct a fluid under pressure upon said blades and in a downward direction.

2. In an agitator riddle, a frame having depending members, an overbalanced rotor mounted between said members upon a vertical axis and formed to present turbine blades, means to direct a motive fluid upon said blades to actuate the rotor and shake the frame, and a riddle mounted on the frame.

3. In an agitator, a frame, including a circular housing, an agitating rotor rotatably mounted within the housing having its periphery formed to present blades and means to direct a fluid under pressure upon said blades and in a downward direction, and an apron adjacent said means and above the rotor.

4. A freely suspended riddle frame having depending supporting members and a housing carried thereby, a fluid pressure rotor mounted upon a vertical axis between said members within the housing, said rotor being overbalanced at one point, so that its

rotation shakes the frame and riddle, and rotor being overbalanced to impart a gyroscopic motion to the frame and screen.

5. In an agitator, a frame, including a circular housing, an agitating rotor rotatably mounted within the housing having its periphery formed to present blades and means to direct a fluid under pressure upon said blades and in a downward direction, a screen supported by the housing adjacent the rotor

10 and an apron secured to the housing between the periphery of the rotor and the screen.

6. In an apparatus of the character described, a frame, a riddle or screen carried by said frame, and a rotating agitator wheel mounted in said frame below the screen, the spokes of said wheel being inclined to create a downward draft.

7. A screening device comprising depending frame members, a rotor housing carried between said frame members, a rotor in said housing provided with peripheral blades, and means to direct a motive fluid upon the blades of said rotor, the rotor being overbalanced so as to vibrate the screen, and means to secure a screen to said housing.

8. A screening device comprising freely suspended depending frame members, a screen supported thereby, a rotor housing also supported between the frame members, an overbalanced rotor mounted within the housing, and means to direct a motive fluid against said rotor in a direction away from the screen.

9. A screening device comprising a freely suspended frame, a screen mounted in the frame, a rotor mounted in the frame in vertical alignment with said screen, said rotor having a peripheral rim of a diameter substantially equal to that of the screen, turbine blades formed on said rim, and means to train a motive fluid against the rotor, said

10. In a screening device, a freely suspended frame, a screen carried thereby, a rotor housing mounted on the frame having a rotor therein provided with peripheral blades, means for training a motive fluid against said blades, and means to deflect said fluid away from the screen.

11. In a screening device, a freely suspended frame, a screen carried thereby, a rotor housing mounted on the frame having a rotor therein provided with peripheral blades, and means for training a motive fluid against said blades in a direction away from the screen.

12. In an apparatus of the character described, a freely suspended frame, a screen carried thereby, an open-ended drum carried by the frame, a spider mounted in said drum and supporting a bearing, an overbalanced rotor mounted in said bearing, and means for training a motive fluid against said rotor to rotate the latter and cause the frame to vibrate.

13. In an apparatus of the character described, a freely suspended frame, a screen carried thereby, a shaft supported by the frame in alignment with the point of suspension thereof, a rotor on said shaft, said rotor having its periphery formed to present turbine blades, said rotor having a peripheral rim of a diameter substantially equal to that of said screen, a weight carried on said rim, and means for training a motive fluid against the blades of the rotor to rotate the same and impart a gyroscopic movement to the frame.

In witness whereof, I have hereunto set my hand this 20th day of December, 1922.

GEORGE B. PICKOP
